UNITED STATES PATENT OFFICE.

CHARLES ROBERT WILLIAMS, OF OMAHA, NEBRASKA.

HAT-VENTILATOR.

1,350,535.

Specification of Letters Patent. Patented Aug. 24, 1920.

Application filed November 12, 1919. Serial No. 337,378.

To all whom it may concern:

Be it known that I, CHARLES ROBERT WILLIAMS, a citizen of the United States, residing at Omaha, in the county of Douglas and State of Nebraska, have invented certain new and useful Improvements in Hat-Ventilators, of which the following is a specification.

The invention relates to attachments for hats and more particularly to an attachment which may be attached to the upper edge of a sweat band and comprising a member hingedly connected to said upper edge of the sweat band and adapted, during warm weather to engage the head of the wearer, in such a manner as to support the front of the hat spaced from the forehead. By so spacing the hat from the forehead the free circulation of air is allowed within the crown of the hat, thereby reducing the amount of perspiration emitted from the pores of the scalp. The circulation of air admitted within the crown of the hat also causing a rapid evaporation of the perspiration that may be emitted from the pores of the scalp.

A further object is to provide a pivoted member pivoted to the upper edge of the hat sweat band, said pivoted member being provided with horizontally disposed spring arms, which are adjustable said hinged member being adapted to be hinged inwardly of the upper edge of the sweat band so that said arms, when it is not desirable to have the hat spaced from the forehead may be disposed between the sweat band and the wall of the crown of the hat. The adjustable arms being flexible, it will be seen that the bow of the arms may be easily reversed when disposed between the sweat band and the crown of the hat.

With the above and other objects in view the invention resides in the combination and arrangement of parts as hereinafter set forth, shown in the drawings described and claimed, it being understood that changes in the precise embodiment of the invention may be made within the scope of what is claimed without departing from the spirit of the invention.

In the drawings:

Figure 1 is a side elevation of a hat showing the attachment applied thereto and the hat being held spaced from the head of the wearer.

Fig. 2 is a horizontal sectional view taken on line 2—2 of Fig. 1.

Fig. 3 is a detail perspective view looking into the crown of the hat and showing the spacing member applied to the sweat band 60 thereof.

Fig. 4 is a detail sectional view taken on line 4—4 of Fig. 3.

Referring to the drawings, the numeral 1 designates a hat and 2 the crown thereof. 65 Secured in the crown is a conventional form of sweat band 3 the upper edge 4 of which is free and not secured to the crown. At the present time hats are not provided with means for ventilating the same except in 70 some hats a series of very small perforations are provided in the crown of the hat. It has been found that such ventilation is so small that it does not materially affect the temperature within the hat, nor do these 75 small perforations allow sufficient ventilation so that the perspiration of the scalp of the head of the wearer may evaporate. To overcome these difficulties and allow a thorough ventilation of the crown of the hat 80 by providing means for spacing the front of the hat from the forehead of the wearer thereby allowing the ingress of air to the interior of the crown 2 substantially around the forehead of the user. To accomplish 85 this result a plate 5 is secured to the outer face of the sweat band 3 said plate 5 being held to the sweat band by sewing or if so desired by cement. Passing through the plate 5, sweat band 3 and reinforcing plate 90 6 is a rivet 7 which securely holds the plate 5 in place and also prevents, in combination with the plate 6 the tearing or sagging of the sweat band 3. Hingedly connected as at 8 to the upper edge of the plate 5 is a 95 plate 9, which plate is adapted to be pivoted upwardly, outwardly and may be disposed between the sweat band and the inner wall of the crown when the spacing device is out of use, for instance during cold weather, or 100 when it is not desired to ventilate the crown of the hat. Slidably mounted in a yoke 10 carried by the plate 9 are overlapping spring arms 11, said spring arms where they overlap being provided with slidable sleeves 105 12 adapted to maintain the overlapping ends in engagement with each other. The arms 11 are preferably made of thin steel or if desired of celluloid. However, they are made extremely thin so as to reduce their 110

transverse cross sectional era to a minimum, this for the reason that when the member 9 is pivoted upwardly and disposed behind the sweat band, said arms will not take up 5 a considerable space. By adjusting the flexible arms 10 and 11 inwardly or outwardly the spaces 13 through which the air passes may be increased or diminished as desired. By the use of flexible arms, it will 10 be seen that when the hinged plate 9 is disposed between the sweat band and the wall of the hat that the flexible arms will bow in the opposite direction to that shown in Fig. 2 and conform to the shape of the hat 15 and head of the wearer. When placing the flexible arms behind the sweat band they are preferably slid into registration with each other so as to reduce their length to a minimum, after which the sweat band may 20 be turned out slightly so that the reverse bowing of the flexible arms 11 may be easily accomplished.

From the above it will be seen that a hat spacing device is provided which may be 25 applied to any form of hat, and one wherein when the device is out of use it will be disposed behind the sweat band.

The invention having been set forth what is claimed as new and useful is:—

30 1. In combination with a hat having a sweat band therein, of a pivoted member secured to said sweat band, said pivoted member being provided with a pair of flexible arms adapted to extend in a horizontal 35 plane and engage the head of the user of

the hat and maintain a space between the sweat band and the head of the wearer, said flexible arms by their flexibility allowing the hinged member and the arms to be disposed behind the sweat band when not in 40 use.

2. The combination with a hat having a sweat band therein, of a pivoted member secured to said sweat band and provided with laterally extending adjustable flexible 45 arms, said arms being adapted to engage the head of the wearer of the hat and maintain a space between the sweat band and the flexible arms for the passage of air, said hinged member being adapted to be disposed behind the sweat band and the flexibility of the head engaging arms allowing said arms to bow so as to also be disposed behind the sweat band when the pivoted 50 plate is placed therebetween. 55

3. The combination with a hat having a sweat band therein, of a pivoted member secured to said sweat band and provided with horizontally disposed flexible arms, said arms having their inner ends overlapped and disposed in a yoke carried by the pivoted member, said yoke allowing the arms to be slid into registration with each other and the flexibility of the arms allowing the hinged member to be pivoted upwardly and outwardly and be disposed between the sweat band and the wall of the 60 hat. 65

In testimony whereof I affix my signature.
CHARLES ROBERT WILLIAMS.
